FOLDABLE VISUAL ALBUM

Frances B. Richman, San Francisco, Calif.

Application July 28, 1942, Serial No. 452,565

6 Claims. (Cl. 281—2)

The invention, in general, relates to mediums for receiving, carrying, graphically or otherwise illustrating and communicating information. More particularly, the invention relates to an improved compact album for visually imparting educational, instructive, training, entertainment or promotional data of various kinds which is contained or receivable therein.

As will appear from the following description, the preferred embodiment of my invention which is illustrated in the annexed drawing possesses a plurality of features which lends the invention admirably to a multiplicity and widely diversified number of commercial as well as educational and entertainment applications. A few of these applications of use of the invention will be alluded to herein but it is to be understood that the scope of the improvement is not to be limited to the specific uses herein mentioned.

A primary object of the present invention is to provide an improved visual album which is adapted to be folded into a packet and which affords the visual dissemination of any desired information.

Another object of my invention is to provide an improved visual album of the indicated nature which is additionally characterized by its simplicity of construction and its inexpensive cost of production.

A still further object of the invention is to provide an album of the aforementioned character which affords the ready insertion therein and removal therefrom of an unlimited number of additional sheets for augmenting the data contained or illustrated therein at any given time.

Another object of my present invention is to provide an improved foldable, visual album of the indicated nature which affords a basic medium for any desired type of informative program whether it be advertising, educational, historical or the like.

The foregoing and other objects are attained in a preferred embodiment of my invention which is illustrated in the accompanying drawing. It is to be understood that I am not to be limited to the precise embodiment shown, nor to the precise arrangement of the several parts thereof, as my invention, as defined in the appended claims, can be embodied in a plurality and variety of forms.

Referring to the drawing:

Figure 1 is a perspective development of a preferred embodiment of the invention.

Figure 2 is a plan view of an embodiment of the present invention, as folded into a packet.

In its preferred form, the foldable visual album of my invention preferably comprises a plurality of main body panels, a plurality of transparent, flexible sheets each of which connects alternate main body panels; said flexible sheets being ac-

cordion pleated and said panels and sheets being adapted to be folded into a packet, together with means for retaining the packet in a closed position.

In Figure 1 of the drawing, I have illustrated a preferred embodiment of the invention wherein there is provided a series of main body panels 111 which are preferably fabricated of a suitable cardboard or relatively stiff paper stock and which are adapted to receive delineations 112 of any desired character for purposes of pictorially, graphically or otherwise visually depicting or disseminating information of any desired type. In this embodiment, the main body panels 111 preferably are connected together in pairs through the medium of a plurality of separate flexible sheets, designated generally by the reference numeral 113, which preferably are fabricated of a transparent material, such as "Cellophane" although such sheets 113 can be fabricated of any other suitable foldable material, as desired. The sheets 113 constitute flexible joints or, in effect, fold lines between adjacent panels 111 in each pair thereof. A suitable adhesive applied to the longitudinal extremities of each of the sheets 113 may be utilized for fastening the transparent sheets to adjacent main body panels 111 and thus joining such main body panels together in pairs. The series of connected pairs of main body panels 111 can be folded upon one another through the media of the transparent sheets 113 into a packet 114, as illustrated in Figure 2 of the drawing. Preferably a cover is provided for attachment to one extremity of the connected main body panels 111, such cover comprising a flap 116 and connected panels 117 and 118, as shown at the left of Figure 1. The panels 117 and 118 may constitute the back and front, respectively, of the cover and preferably although not necessarily are cut somewhat larger than the main body panels 111 of the album. In one form of construction, the series of main body panels 111 can be fastened by any suitable means, such as an adhesive and through the medium of an end flap 119, to the back of the back panel 117 of the cover, as indicated in Figure 1. To hold the packet together in closed position, a conventional snap fastener 121 can be provided to fasten the flap 116 to the top of the front panel 118 of the folded album, as indicated in Figure 2 of the drawing. If desired, the back and front cover panels 117 and 118 can be omitted, as well as the flaps 116 and 119, and the opposite ends of the panels 111 can constitute the front and back of the folded album and can be secured together by a suitable snap fastener. The transparent sheets 113 of the album are creased transversely at spaced intervals, or accordion pleated, to provide a series of connected transparent panels 124 having fold lines 113 therebetween. Each of the transpar-

ent panels 124 can be utilized to carry any desired indicia which may supplement the indicia on the main body panels 111 or which may be wholly unrelated thereto, as desired. It may be observed also that supplement media, in the form of cards, tickets, paper sheets or the like can be carried within the folds of the transparent sheets 113, when folded together, so that such sheets constitute, per se, holders or pockets as well as indicia-bearing media.

It is to be especially observed that in my improvement herein illustrated the main body panels are all adapted to receive delineations of any desired indicia on the obverse as well as the reverse thereof so that each foldable album provided in accordance with my invention affords illustrations, indicia or delineations which are visible from each side of the main body panels when extended, as illustrated. The composite construction including the transparent sheets affords a series of multiple books which may contain graphic, pictorial or photographic illustrations in part and written or typewritten indicia in part.

With further reference to Figures 1 and 2 of the drawing, depicting the preferred embodiment of my invention in extended as well as in packet form. This embodiment has many commercial applications and can be utilized either as an advertising medium in its entirety, a sales promotional catalogue, an educational or entertainment packet for either children or adults, or as a training manual or booklet for men in the armed services of the country. For example, as indicative of its use as an advertising medium, the main body panels 111 of the embodiment of Figure 1 of the drawing can be delineated with cuts or graphic illustrations pertaining to the merchandise of a particular concern. The transparent sheets 113 of this embodiment can carry messages relating to the goods and merchandise depicted on the main body panels 111, or such transparent sheets can be slotted to receive tickets or premium cards or the like handed to patrons of the concern in return for purchases or as a premium therefor. The end flap 116 of the cover of the folded album can be delineated with a facsimile of a negotiable instrument, such as a check which is designated by the reference numeral 120 in Figure 2 of the drawing, or with other goodwill token advising the patron that the check or token will be honored by a community restaurant or other merchant for the value specified therein when the packet or album containing a designated number of premium tickets or cards is presented to such community concern. Another application of use of the preferred embodiment of the invention illustrated in Figure 1 of the drawing can be for children's educational programs; the main body panels 111 being delineated with pictures of animals or parts of animals while the transparent sheets 113 can be delineated with suitable legends relating to the pictures on the main body panels 111 and supplemental thereto so that when the folded sheets overlie the main body panels 111 the children can visualize a complete pictorial representation of a given animal or group of animals and their habitats. The embodiment of Figure 1 can admirably serve as a stamp album wherein the main body panels 111 can serve to hold the stamps and the transparent sheets 113 can be used for entering supplemental data relating to the countries identified by the stamps. As an educational

medium for adults, or training manual for men in the service, the main body panels 111 can be delineated with representations of tanks, aeroplanes, guns, gun carriages and other military equipment, while the transparent sheets 113 can carry informative data as to the qualities of the craft with detailed specifications. Or such transparent sheets 113 can initially be entirely or partially blank to be filled in with data uncovered

10 by the students or men under instruction from other sources, thereby affording the compilation of a completed work album with partial illustrative matter and partial written or typewritten information.

15 I claim:

1. A foldable visual album consisting of a plurality of main body panels each comprising a sheet of relatively stiff, inflexible material; all of said main body panels being adapted to receive delineations of any desired indicia on the obverse as well as reverse face thereof, and a plurality of flexible sheets each of which is connected to alternate main body panels; each of said flexible sheets being accordion pleated; said main body panels and said flexible sheets being adapted to be foldable together into a packet.

2. A foldable visual album consisting of a plurality of main body panels each of which comprises a relatively stiff, inflexible sheet; all of said main body panels being adapted to receive delineations of any desired indicia on the obverse as well as the reverse face thereof, and a plurality of flexible sheets each of which is connected between alternate main body panels and which forms an extensible joint therebetween; said flexible sheets being accordion pleated to form recesses therein which are adapted to receive cards or the like.

3. A foldable visual album consisting of a plurality of main body panels each of which comprises a relatively stiff, inflexible sheet; all of said panels being adapted to receive delineations of any desired indicia on the obverse as well as reverse face thereof, a plurality of transparent, flexible sheets each of which is connected between alternate main body panels; said transparent flexible sheets being accordion pleated and being adapted to be folded independently of said main body panels as well as to be foldable upon said main body panels so that the entire group of panels and flexible sheets can be folded into a packet, and means for retaining the packet in a closed position.

4. A foldable visual album consisting of a plurality of main body panels fabricated of relatively stiff material; each of said panels being adapted to receive delineations of any desired indicia on the obverse as well as reverse face thereof, and a plurality of transparent, flexible sheets each of which connects alternate main body panels to form extensible joints between said main body panels; said transparent, flexible sheets being accordion pleated to provide recesses therein for the reception of cards or other material and also being adapted to be folded upon said main body panels without obscuring any indicia delineated on said panels.

5. A foldable visual album as defined in claim 1 and including means for holding the packet in a closed position.

6. A foldable visual album as defined in claim 4 and including means for retaining said panels and sheets in closed packet form.

FRANCES B. RICHMAN.
